UNITED STATES PATENT OFFICE.

FRANK R. WEAVER, OF CLINTON, WISCONSIN, ASSIGNOR TO WISCONSIN KNIFE WORKS, INC., OF CLINTON, WISCONSIN, A CORPORATION OF WISCONSIN.

CUTTER.

Application filed February 9, 1927. Serial No. 166,844.

This invention relates to cutters for wood working machinery and is more particularly concerned with the provision of a novel type of moulder head.

5 The principal object of my invention is to provide in a head of the type referred to, wherein a plurality of bits of one pattern are mounted in spaced relation about the periphery of the head with a plurality of 10 bits of another pattern mounted between the first mentioned bits to make complementary cuts in the work, novel means for holding the last mentioned bits permitting the rotation thereof in the plane of their operation 15 to inoperative positions whenever desired as, for example, when the first mentioned bits are to be tracked and trued up. With the means employed in accordance with my invention the rotary bits may be set accurately 20 in their proper position, and the simple matter of loosening one nut suffices in the retracting of each bit from its normal cutting position, and the tightening of the nut after the blade is moved back to its normal 25 position serves to fasten the same securely, no resetting of the blade being required as was the case in other heads with which I am familiar.

30 These and other important objects and advantages of my invention will be discussed in the following specification wherein reference is made to the accompanying drawings illustrating a preferred embodiment.

35 In the drawing Figure 1 is a perspective view of a cutter embodying the features above referred to.

Fig. 2 is a sectional detail on a slightly enlarged scale to show the clamping means for the dove-tailed bits and to indicate the 40 capacity for endwise and sidewise adjustment of the bits. This view is taken on line 2—2 of Fig. 1;

45 Fig. 3 is a sectional detail on a similar scale to show the clamping means for the other set of bits with which the present invention is particularly concerned, and to indicate also the capacity for adjustment and the retractability of the bits. This view is taken on the line 3—3 of Fig. 2; and

50 Fig. 4 is a plan view of the next bit of the same set to show how alternate bits of this set are canted in one direction while intermediate ones are canted in the other direction.

55 The same reference numerals are applied

to corresponding parts throughout the views.

The moulder head shown is equipped with two sets of bits for cutting the ogee curves and the intermediate groove in the edges of strips used in making windows and doors in sash work, or in the making of cabinets and the like. The particular pattern or profile to be cut is, however, of no special importance, generally speaking, and may be varied as required, although the present improvements are particularly advantageous when embodied in a moulder head for the purpose referred to, as will presently appear. The head is indicated generally by the reference numeral 5 and has an opening 6 to permit the mounting of the head on a spindle in the usual manner. The head is equipped with four dove-tailed bits designated by the reference numerals 7, and four plain bits designated by the reference numerals 8. The 60 particular number of bits is, however, of no special importance. The bits 7 are milled lengthwise of the outer face as indicated at 65 9 and are bevelled at the front end as indicated at 10 to make the cutting edge, the degree of bevel being predetermined according to the depth of the cut and to secure the proper shaped ogee curves. The bits 8 have side cutting edges 11 and peripheral cutting edges 12 to cut the groove between the ogee 70 curves. The alternate bits have their side cutting edges disposed at one side and the intermediate bits have their side cutting edges disposed at the other side to make a 75 finishing cut at the opposite sides of the 80 groove. The bits 7 are arranged on seats 13 and are serrated on the under face, as indicated at 14, to match corresponding serrations on the seats 13, the serrations being 85 transverse, relative to the plane of operation 90 of the head. Thus the bits 7 may be adjusted endwise by entering the serrations of the 95 bits in the proper serrations on the seats in an obvious manner, and the bits are furthermore adjustable laterally in any position of 100 endwise adjustment by sliding the serrations of the bits in the serrations of the seats. The endwise adjustment is for wear and to compensate for grinding of the bits, while the lateral adjustment is for the purpose of 105 properly tracking the bits. The clamping means for the dove-tailed bits will be presently described in detail. The plain bits 8 are pivotally mounted in recesses 15 provided in the periphery of the head 5, between the 110

seats 13. The pivotal mounting of the bits permits of their being turned from the operative position shown, into an inoperative position where the cutting edge is removed 5 from the cutting radius to what may be termed a retracted position. The details of the mounting of these bits and the means for clamping the same will also be described presently. From the description thus far 10 advanced it will appear that the retracting of the bits 8 leaves the bits 7 alone on the cutting radius. It is therefore a simple matter to track the bits when setting up the cutter. This feature is, however, of special ad- 15 vantage in the matter of truing up the bits since it makes possible the use of a closed end stone, having the profile to fit the end of the milled groove 9. Where the bits had a tooth extending lengthwise of the groove 9 to 20 cut the groove between the ogee curves on the work, the matter of truing up the bits became very involved. An open-ended stone, the opening in the end of which accommodated the middle tooth referred to, had to be em- 25 ployed or else other equally involved measures had to be adopted to true up the bits. In the present case the retractability of the intermediate plain bits eliminates the difficulties referred to and the bits are further- 30 more of a much less complicated pattern than was otherwise required for the production of the kind of work in question. There is ob- 35 viously much less chance of clogging the bits where the pattern is as plain as in the pres- 40 ent case.

Referring now to Fig. 2 it will be observed that the bit 7 illustrated is dove-tailed on its under side, as indicated at 16, for clamping purposes. A pair of side plates 17 serve as 45 clamping members and have bevel faced edge portions 18 serving as jaws for oppositely engaging the dove-tail 16 of the bit. The plates 17 bear only at 19 against the opposite sides of the head 5 so as to have 50 capacity for limited rocking movement relative to the head, as required in the side to side adjustment of the bit or blade. If desired a pair of pins 20 may be provided on the head to position each plate while permitting of the slight rocking movement referred to. The plates 17 are arranged to be drawn together to clamp the bit and for this purpose a bolt 21 is provided, secured as by 55 means of a pin 22 in the head 5, and projecting through openings in the plates 17 for the reception of nuts 23 on the threaded extremities thereof. The tightening of the nuts 23 clamps the bit with a vice-like grip between the jaws 18. The loosening of one 60 of the companion nuts, accompanied by the tightening of the other, and vice versa, will result in a corresponding adjustment either way of the bit, and it will be held just as firmly in one position as in another.

65 Referring now to Figs. 3 and 4, wherein

is illustrated the blade holding means with which the present invention is more particularly concerned, it will be observed that the bits 8 are received in the recesses 15 between walls 24. A pair of blocks 25 of dove-tail 70 form are received in openings 26 of complementary form provided in the walls 24, the blocks projecting substantially half-way from the openings at the periphery of the head. The bit 8 is received between the 75 blocks 25 on a bolt 27, the latter being received in registering openings 28 and 29 provided in the two blocks. The opening 28 is threaded for the threaded reception of the bolt 27, but the bolt extends freely 80 through the opening 29. The blocks 25 are both split at the base portion, as indicated at 30, and arranged to be spread into holding engagement in the openings 26 such as will prevent endwise displacement of the 85 blocks and a resulting sidewise displacement of the bit. The blocks are both counter-bored, as indicated at 31, and receive tapered collets 32 which are passed over the projecting ends of the bolt 27. Nuts 33 and 33' thread on the projecting ends of the bolt 27 and jam against the collets 32. When the nuts are tightened the blocks 25 are drawn together into clamping engagement with the opposite sides of the bit 8 90 and, at the same time, the blocks are spread by reason of the action of the collets 32 so that the blocks are held against movement in their openings 26. Obviously the 95 bit is held in a very secure manner. When 100 it is desired to turn the bit from its cutting position to a retracted position, this is done simply by loosening the nut 22 without disturbing the nut 33'. This leaves the block associated with the nut 33' wedged in its opening, whereas the other block is free in its opening and the bit, consequently, can be turned around relative to the bolt 27. The reason for threading the bolt 105 27 in the opening 28, it is believed, will now 110 be apparent. The only time the nut 33' is loosened is when the two blocks are to be moved together one way or another in setting the bit. However, once the bit has been set the nut 33' is left tightened and 115 only the nut 33 is loosened on the occasion of retracting the bit. After a bit is retracted it can be returned to its normal cutting position and clamped again in this position without necessitating a resetting thereof, 120 since the one block has not changed its position during the retracting of the bit but has remained tightly wedged in its opening.

125 It will be observed by comparison of Figs. 3 and 4 that the bits 8 are canted so that the side cutting edge 11 of one bit is disposed toward one side of the head while the side cutting edge 11 of the next bit of the same set, is disposed toward the opposite side. This positioning of bits results in 130

a finishing cut at both sides of the groove produced by the bits. The inner end face of the block 25, designated by the reference numeral 34, determines the cant of the bits 5 in an obvious manner and I prefer to provide these parallel end faces on the two blocks by providing a single block from which the two blocks are to be formed, setting the block in the head in the openings 10 26, and milling through the block in the recess 15 at the proper angle to cut the block in two and accordingly provide the end faces at the proper angle. Thus the cant of the blade is positively determined 15 irrespective of any discrepancy in the milling of the openings 26 or in the forming of the blocks.

I claim:

1. In a cutter, the combination of a head 20 providing spaced walls thereon for the mounting of a blade therebetween, a blade, clamping blocks for holding said blade received in openings provided in said walls, a clamping bolt passing through said blocks 25 and through the blade held therebetween, and nuts threaded on the opposite ends of said bolt and drawing the blocks together to clamp the blade therebetween.
2. A structure as set forth in claim 1 30 wherein at least one of said blocks is split to permit the spreading thereof into holding engagement in its opening.
3. In a structure as set forth in claim 1, wherein at least one of said blocks is split 35 to permit the spreading thereof into holding engagement in its opening, the provision of means operated in the tightening of said nuts arranged to spread the block in its opening.
4. In a cutter, the combination of a head 40 providing spaced walls thereon for the reception of a blade therebetween, a blade received between said walls and arranged to project from the periphery of the head in operation, a pair of clamping blocks for oppositely engaging the blade and received in 45 openings in said walls, at least one of said blocks being split whereby to permit the spreading thereof into holding engagement in its opening, a bolt passing through said blocks and through the blade held therebetween, said bolt being threadedly received in the aforementioned split block, nuts 50 threading on the opposite ends of said bolt arranged to draw the blocks together to clamp the blade therebetween, the split block being counter-bored at its outer end about

the projecting end of the bolt, and a tapered collet received in said counter-bore behind the nut on said bolt whereby in the tightening of the same to spread said block into holding engagement in its opening. 60

5. A structure as set forth in claim 4 wherein the split block is of a dove-tail form and split at the base of the dove-tail, the 65 opening receiving said block being of complementary form to receive the base portion of the dove-tail block whereby the block serves not only to clamp the blade but to hold the same against lateral displacement 70 and against turning.

6. In a cutter, the combination of a head providing spaced walls thereon for the reception of a blade therebetween, a blade disposed between the walls to project from the periphery of the head in operation, a bolt for mounting said blade to permit rotation thereof in the plane of its operation from cutting position to an inoperative position, a pair of clamping blocks of dove-tail form 75 received in openings of complementary form provided in said walls to permit opposite engagement of said blade, said blocks being split to permit the spreading thereof in their openings to hold the same in position, said bolt being received in registering openings 80 in said blocks and having the opposite ends thereof threaded and projecting from the outer ends of said blocks, said blocks being counter-bored at their outer ends about the 85 projecting ends of said bolts, tapered collets received in said counter-bores and nuts threaded on the ends of said bolt arranged to jam against said collets, whereby to draw the blocks together to clamp therebetween 90 and simultaneously spread the blocks rigidly 95 into holding engagement in their openings whereby to prevent lateral displacement of the blade.

7. A structure as set forth in claim 6 100 wherein the bolt is threadedly received in one of said blocks but passes freely through the opening in the other block for the purpose specified.

8. A structure as set forth in claim 6 105 wherein the inner ends of said blocks which abut the opposite sides of the blade are disposed at an angle to the plane of operation of the head to correspondingly cant the blade held therebetween. 110

In witness of the foregoing I affix my signature.

FRANK R. WEAVER.
